BY

X. S. M. ATTORNEY

Patented Nov. 1, 1927.

UNITED STATES PATENT OFFICE.

FREDERICK WALLACE STULL, OF TORRINGTON, CONNECTICUT.

AUTO SIGNAL.

Application filed June 13, 1924. Serial No. 713,748.

My invention relates particularly to apparatus for indicating the intention of the driver to change direction or movement of the vehicle.

5 The main object is to provide a simple, inexpensive, and reliable form of device. Another object is to provide a device of this character which can be readily attached to and detached from a vehicle. An other object is to provide a structure of this character which serves as a signal at night as well as by day.

In carrying out the invention I provide a vertical standard with clamps for attaching it to the windshield support or dash of a car. To this standard I hinge a signaling arm which is provided with a handle for operating it. The standard is provided with clips for holding the arm in its non-signaling position, as well as in its signaling position. I also prefer to provide electrical contacts so that a lamp may be lighted automatically as the signaling arm is swung out into view.

25 Figure 1 is an edge view taken from the left and showing the device in its non-signaling position.

Figure 2 is the rear view of the same, showing the arm in dot and dash lines in 30 the signaling position.

Figure 3 is a horizontal section and plan on the plane of the line 3—3 of the Figure 1.

Figure 4, is a horizontal section and plan 35 on the plane of the line 4—4 of the Figure 1.

I have indicated an ordinary standard or post of a windshield frame by the reference numeral 5 in Figures 1 and 3. The standard 6 of the device is preferably in the form of a channel member and provided with two clamps 7 and 8 adapted to be readily attached to the supporting post 5 of the vehicle so that the device can be 45 readily applied by anyone in a very few moments and without requiring any tools except a wrench.

The signal member 9 is preferably in the form of a casing containing one or more 50 electric lamps. This is secured to the end of a tubular arm 10 which is hinged at 11 to lugs near the lower end of the standard 6. The lower end of the arm 10 is provided with a handle 12 which preferably 55 extends somewhat to the right and to the

rear for convenience in operation of the device.

To the upper end of the standard 6 I attach a spring clip 13 in a convenient manner, for instance, by a screw 14. This clip 60 is so arranged as to yieldingly grasp the arm 10 near its upper end and hold the signaling device yieldingly in its vertical or non-signaling position so that it will not be jarred loose by the vibrations of the car 65 and yet so that it is easy to swing the signaling arm by simply pulling up on the handle 12.

Such a device is of course useful for signaling in the daytime but at night a light 70 is essential to attract the necessary attention. I, therefore, prefer to provide a switch with one or more stationary contacts 15 so as to automatically light the lamp in the casing 9 as the arm is swung 75 outward and downward. This contact member is located in such a position that the circuit is established a considerable time before the arm reaches its lowest position. As a result of this the light is turned on as 80 the arm swings outward and the fact of a moving light is thus produced since the light remains on as the arm continues to swing outward and is only extinguished when the arm leaves the contact 15 on its 85 way back. This contact clip 15 may conveniently be carried by projection 16 secured to the stem near its lower end, this projection serving to support the arm in 90 its horizontal position.

It will be noted that when the arm is in its vertical position it is housed throughout the greater part of its length within the channel of the standard 6 directly in line with the support 5. This enables me to 95 provide a compact device which has a maximum strength at a minimum expense. The device is so compact that it obstructs the vision but little if any more than the ordinary windshield support. Furthermore the 100 construction is such that it can be readily applied to any of the ordinary types of automobiles in a very convenient place for operation and without being in the way.

For the purpose of attracting attention or 105 special signaling, I may provide the casing 9 with two or more different colored glasses 17 and 18 and one or more lamps, such as 19 and 20, adapted to be controlled in any 110 desired manner. Obviously the glass of the

2
signaling device may be provided with any suitable indicating arrow or word indicating the intention to stop or turn to the right or left.

5 It should also be understood that I prefer to have both the front and rear of the casing transparent or translucent so that the signal light will be visible from the front of the vehicle as well as from the rear.

10 I claim:

1. A signaling device comprising a vertical standard, clamps projecting from the upper and lower ends thereof and adapted to be readily attached to the wind-shield support of an automobile, a signaling arm hinged near the lower end of said standard, a spring clip secured to the upper end of said standard, and yieldingly engaging said arm, said arm having a handle projecting from its lower end.

15 2. A construction of the character set forth in claim 1 in which the standard is of channel form and normally receives the signaling arm when in its upright position.

25 3. A signaling device comprising a channel standard, an arm hinged therein near its lower end, a spring clip at the upper end of said standard yieldingly engaging said arm, and a handle extending from the inner end of said arm rearward and to the right.

30 4. A signaling device comprising a vertical standard, means for securing it to a support, an arm hinged at the lower end thereof

adapted to swing outwardly therefrom, a handle projecting from the end of said arm, a spring clip carried by said standard for holding the upper end of said arm in the non-signaling position, and a spring clip secured to said standard adjacent the hinge of said arm for holding said arm in its signaling position.

5 A signaling device comprising a standard, means for securing it in vertical position on an automobile, an arm hinged at its lower end to the lower end of the standard to swing outwardly and downwardly, a handle projecting from the end of said arm, a spring clip on said standard for holding the upper end of said arm in the non-signaling position, and means connected with said standard for supporting said arm in its signaling position.

6. A signaling device comprising a channeled standard, means for securing it in vertical position on an automobile, an arm hinged at its lower end to said standard to swing outwardly and downwardly from a position in the channel of said standard, a handle projecting from the lower end of said arm, a spring clip for engaging and holding in said channel the upper end of said arm in the non-signaling position, and a support on said standard adjacent the hinge of said arm and beyond the pivot of said hinge for holding the arm in its signaling position.

FREDERICK WALLACE STULL.
